UNITED STATES PATENT OFFICE.

MARTIN KENNEDY, OF CHICAGO, ILLINOIS, ASSIGNOR OF ONE-HALF TO
WILLIAM RENSHAW, OF CHICAGO, ILLINOIS.

DRAFT-RIGGING FOR FREIGHT-CARS.

No. 802,514.

Specification of Letters Patent.

Patented Oct. 24, 1905.

Application filed January 6, 1905. Serial No. 239,911.

To all whom it may concern:

Be it known that I, MARTIN KENNEDY, a citizen of the United States, residing at Chicago, in the county of Cook and State of Illinois, have invented certain new and useful Improvements in Draft-Rigging for Freight-Cars, of which the following is a specification.

My invention relates to improvements in draft-riggings for freight-cars.

10 The object of my invention is to provide a draft-rigging that will effectively distribute the shock resulting from coupling and operating a train, to prevent accidental detachment of the draw-bar, and to protect the ends of the 15 cars.

A further object is to provide a cheap, light, and durable draft-rigging which shall simplify car construction and which may be readily inserted in place and easily removed when 20 desired.

These and such other objects as may hereinafter appear are attained by my invention, the preferred embodiments of which are shown in the accompanying drawings, in which—

25 Figure 1 is a side elevation showing my draft-rigging applied to a car having a metallic frame. Fig. 2 is a plan view of Fig. 1. Fig. 3 is an end elevation, partly in section, on the line 3 3 of Fig. 2 looking in the direction indicated by the arrows. Fig. 4 is a 30 cross-section on the line 4 4 of Fig. 2, looking in the direction indicated by the arrows. Fig. 5 is a longitudinal section through a part of a wood construction-car provided with my 35 draft-rigging. Fig. 6 is a horizontal sectional view of Fig. 2. Fig. 7 is an end elevation, partly in section, on the line 7 7 of Fig. 6 looking in the direction indicated by the arrows. Fig. 8 is a cross-section on the line 8 8 of Fig. 40 6 looking in the direction indicated by the arrows. Fig. 9 is a plan view of the preferred form of my improved draft-rigging. Fig. 10 is a plan view of a modification thereof. Fig. 11 is a vertical cross-section on the line 11 11 45 of Fig. 1, and Fig. 12 is a vertical cross-section on the line 12 12 of Fig. 1.

Like letters of reference indicate the same parts in the several figures of the drawings.

Referring by letter to the accompanying 50 drawings, A represents the draw-head, provided with a shoulder A', arranged parallel to the end of the car; B, the draw-head pin; C, the draw-bar, terminating in an enlarged T-head C'; D D, metallic draft-arms, compris-

ing enlarged front portions D' D' and rear 55 portions D'' D''. The front portions D' D' have within themselves a recess E, within which the T-head C' of the coupler plays. At the end of the recess is a pocket E', within which is loosely seated a spring F, adapted to engage 60 the end of the T-head C'.

At the front wall of the recess E' are preferably fitted renewable wearing-strips G G, and on the shoulders C' are fitted corresponding wearing-strips G' G'. The draft-arms D D 65 are secured together by means of bolts H H or in any other suitable manner.

In fitting the draft-rigging and coupler in a car having a metallic body a portion of the end is cut away at I I to receive the ends J J 70 of the draft-arms. The draft-rigging and coupler are secured in place by any suitable means—such, for example, as straps K K, secured to the ends J J of the draft-rigging and to the end of the car by bolts K' K', and also 75 in the rear by means of bolts L L through the ends of the arms and the body-bolster M. The draw-bar is held in place in the draft-rigging by means of a front carrier O and a bottom carrier P, secured to the bottom of 80 the rigging. If additional support is desired, rods T may be passed through the holes Q Q in the arms and secured to the floor of the car R. I may, if preferred, cut away sufficient 85 of the end to allow the passage of the shank of the coupler, in which event the end of the draft-rigging would fit closely against the end of the car. When it is desired to remove the draft-rigging, the carrier O is removed and the bolts L L and K' K' sheared off, where- 90 upon the draft-rigging will drop out of place.

Referring to Figs. 5 and 6, in which the draft-rigging and coupler are shown in place in a car with a wooden frame, the only essential differences are that the structure is fastened to the stringers S of the car by means of the rods T passing through the bolt-holes Q Q in the rigging, and also by means of a strap U passing under the front portion of the rigging and secured thereto by bolts U' 95 and also bolted to the end sill of the car. The draft-rigging in this construction closely abuts the body-bolster M.

In Fig. 10 I have illustrated a modification of my invention, in which the draft-rigging 105 d is made in one piece.

Fig. 11 shows in detail the method by which the front carrier O is secured to the draft-

rigging by means of bolts V V, and Fig. 12 shows in detail the method by which the bottom carrier P is secured to the draft-rigging by means of bolts W W.

5 When my improved draft-rigging is in position and cars coupled together are subjected to a pulling strain, this strain is transmitted through the T-head C' against the wearing-strips G G', and thence the strain is transmitted through the entire structure and also through the body-bolster. If the car is at rest when this strain is applied, the spring F is in released position and has pushed the T-head against the front of the recess, so that 15 there is no impact. When the cars are coupled, the force of impact is first exerted to compress the spring F, and thus diminish the force of impact. The length of the recess E is so proportioned that when the face A' of the 20 coupler-head abuts the ends J J of the draft-arms the end of the T-head simultaneously strikes the rear end of the recess E, and the shock is thus transmitted and distributed through the draft-arms and against the body-bolster and against the metallic end sill.

25 While I have shown renewable wearing-strips on the faces of the recess and T-head, I may dispense with them, if desired.

Coupler-heads now in use embody a curved 30 face with a small bearing-surface on one side thereof. The use of this construction is very destructive to the ends of the cars or to the buffer-plates interposed between the face of the coupler and the end. Constant switching of 35 the cars with the consequent repeated impact of this coupler against the buffer-plates soon splinters the dead-wood block, if it be wood, or indents it, if it be metal, with a correspondingly-injurious effect upon the end of 40 the car itself. In my construction the shoulder on the coupler-head surrounds the shank and is parallel with the end of the car or draft-rigging, and thus presents a large impact-surface with a correspondingly-decreasing 45 liability to injure the end of the draft-rigging.

My draft-rigging as constructed embodies 50 very few parts and is easily assembled and put in place and as easily removed from the car when desired without practically dismantling the car, as in other devices, while the draft-arms also serve, in effect, as stringers for the car-frame.

Injury to the draft-rigging is a principal 55 source of damage to which cars are liable, as an inspection of cars sent in for repairs will show that more than seventy-five (75%) per cent. are so damaged. In all structures of this character the element of cost depends largely upon the number of parts used and 60 the weight of the material. By the use of my improved draft-rigging I am enabled to dispense with the use of over eight hundred (800) pounds of material required in draft-rigging of other types and am able to effect 65 a great saving in weight as against all other

types of draft-rigging and at the same time accomplish the result by the use of fewer parts than required in any construction now in use.

While I have illustrated two forms of draft-rigging, it is evident that other modifications may be used without departing from the spirit of my invention.

I claim—

1. As a new article of manufacture, a metallic draft-rigging, comprising draft-arms secured together and rigidly secured to the end of the car, said draft-arms being provided with an interior recess terminating in a pocket, said recess having wearing-strips upon its front face.

2. As a new article of manufacture, a car-coupler comprising a coupler-head having a flat base at right angles to the shank, and a shank terminating in a horizontal T-head, the shoulders of said T-head being provided with wearing-strips.

3. In an article of the class described, the combination with a car, of a metallic draft-rigging provided with a recess, a pocket, a coupler having a face at right angles to the shank thereof and terminating in a horizontal T-head seated within said recess, a spring, seated within said pocket, adapted to rest against the T-head, said recess and T-head being provided with wearing-strips.

4. In an article of the class described, the combination with a car, of a metallic draft-rigging provided with a recess, a pocket, a coupler having a face at right angles to the shank thereof and terminating in a horizontal T-head seated within said recess and secured in place by means of carrier-plates, and a spring seated within said pocket and adapted to rest against the T-head, said recess and T-head being provided with wearing-strips.

5. In an article of the class described, the combination with a car, of a draft-rigging, a coupler having a face at right angles to its shank, said shank terminating in a horizontal T-head loosely fitted within a recess in the draft-arms, said coupler and recess being so proportioned that, when the face of the coupler-head rests against the ends of the draft-arms, the ends of the T-head will rest against the end of the recess.

6. In a draft-rigging, the combination with a car-frame, of a draft-beam provided with a recess adapted to receive the rear end of a draw-bar, the rear wall of said recess being arranged to provide an abutment for the rear end of said draw-bar, and a draw-bar extending through the end sill of the car and into said recess, said draw-bar being provided with a shoulder adapted to abut against the end sill of the car at the same time that the rear end of said draw-bar strikes said abutment in said recess, substantially as described.

7. In a draft-rigging, the combination with a car-frame, of a draft-beam mounted within

5 said car-frame, said draft-beam being provided with a recess adapted to receive the rear end of a draw-bar, said recess being provided with an abutment for the rear end of the draw-bar and being also provided with means for receiving a buffer-spring adapted to engage the rear end of the draw-bar, and a draw-bar extending through the front sill of the car into said recess and provided with a shoulder, all so arranged that, whenever said shoulder strikes the front sill of the car, the rear end of the draw-bar will simultaneously strike the abutment provided therefor in said recess, substantially as described.

10 8. In a draft-rigging, the combination with a car-frame, of a draft-timber mounted within said frame and extending from the end sill to the transom-bar, said draft-timber being provided with a recess adapted to receive the rear end of the draw-bar and provided with means for affording an abutment for the rear end of the draw-bar, a buffer-spring mounted within said recess and arranged to engage the rear end of the draw-bar, a draw-bar extending through the end sill of the car into said recess and against said spring, said draw-bar being provided adjacent to its forward end with a shoulder, all so arranged that said shoulder will abut against the end sill at the

15 same time that the rear end of the draw-bar strikes the abutment provided therefor in said recess.

9. In an article of the class described, the combination with a car, of a draft-rigging, a coupler comprising a coupler-head and shank, 35 said shank terminating in a T-head loosely fitted within a recess in the draft-arms, said coupler and recess being so proportioned that, when the coupler-head rests against the ends of the draft-arms, the end of the T-head will 40 rest against the end of the recess.

10. In a draft-rigging, the combination with a car-frame, of a draft-beam secured thereto, a draw-bar provided at its rear end with shoulders, said draft-beam being provided with a recess adapted to receive the rear end of said draw-bar, said recess being provided with an abutment for the rear end of said draw-bar and also with means for engaging said shoulders on said draw-bar head when the draw-bar is moved forwardly, said draw-bar being also provided adjacent to its forward end with a shoulder, all so arranged that, whenever the shoulder of the forward end of the draw-bar abuts against the end 50 sill of the car, the rear end of the draw-bar will simultaneously abut against the abutment provided therefor in said recess, substantially as described.

MARTIN KENNEDY.
